UNITED STATES PATENT OFFICE.

JOSEPH L. R. HAYDEN, OF SCHENECTADY, NEW YORK, ASSIGNOR TO GENERAL ELECTRIC COMPANY, A CORPORATION OF NEW YORK.

METHOD OF PRODUCING A FLAMING OR LUMINOUS ARC.

1,190,162.

Specification of Letters Patent.

Patented July 4, 1916.

Application filed April 25, 1911. Serial No. 623,236.

To all whom it may concern:

- Be it known that I, JOSEPH L. R. HAYDEN, a citizen of the United States, residing at Schenectady, in the county of Schenectady, State of New York, have invented certain new and useful Improvements in the Method of Producing a Flaming or Luminous Arc, of which the following is a specification.
- 10 My invention has reference to an arc lamp, and particularly to an arc lamp in which are used electrodes between which a flaming or luminous arc is produced. In such a lamp, as is well known, most of the 15 light is emitted from the arc itself as distinguished from the incandescent tips of the electrodes as in the case when plain carbon electrodes are used with direct currents. In a flaming or luminous arc, therefore, even 20 though the arc remains steady, any variation in the amount of light-producing vapors in the arc will cause an objectionable corresponding variation in the light emitted from the lamp. Now it has been found that 25 many of the materials which produce the best light in a lamp of the character described give an arc which is long and thin and very unsteady, this being particularly true of titanium and titanium compounds, 30 which are among the best materials for producing a flaming or luminous arc. In order to give to the arc reasonable steadiness, it becomes necessary to use in conjunction with the light-giving material a material that 35 operates to steady the arc, and this has hitherto been done by admixing such steady- 40 ing material with the light-giving material. Such steady-ing materials fatten the arc and make it more conductive, and thereby make 45 the arc steady. At the same time such steady-ing materials are more easily fusible and vaporizable than are the best light-producing materials, such as metallic titanium, titanium carbid, and other titanium 50 compounds, with the result that such steady-ing materials when mixed with the light-giving materials are at times taken into the arc to the exclusion of such light-giving materials, which latter are very refractory, and 55 the arc thus has a tendency to vaporize from the electrode everything except such light-giving material. The arc will therefore take up the steady-ing material until it is compelled to vaporize the light-giving material, because of the absence of any other

material at the arcing surface. The result of all this is that the proportion between the amount of vapors from the light-giving material and from the steady-ing material does not remain constant in the arc, and 60 there is a wide variation between the intensity or the color or both the intensity and the color of the light from the two materials, this variation depending upon the character of the materials used; and, although the arc remains reasonably steady, 65 the light emitted therefrom is unsteady. I find, for instance, that an electrode made of titanium carbid and calcium fluorid gives a very efficient and fairly steady arc, but the 70 light emitted therefrom is unsteady, fluctuating between the white titanium light and the yellow calcium light.

I have found that I can produce a steady 75 arc and at the same time keep the light emitted therefrom steady in a lamp of the character described by introducing the light-giving vapors to the arc from one of the electrodes and the steady-ing material from the other electrode.

While not limited thereto, my invention is particularly applicable to circuits in which alternating currents are used, in which case during one-half period of the alternating current the electrode containing the light-giving material furnishes the vapors of such material for the arc, while during the other half period of the current the other electrode furnishes the steady-ing material for the arc, thereby fattening the arc and giving 90 conductivity to the same.

In its more specific aspects, therefore, my invention comprises the process of introducing a light-producing material into the arc from one electrode and a steady-ing material 95 from another electrode as well as the combination of two such electrodes. In its broader aspects, however, it covers the introduction of any two materials into the arc which do not enter uniformly into the arc when they 100 issue together from the same electrode.

I have shown one embodiment of my invention in the accompanying drawings, in which—

Figure 1 is a side view of the electrodes 105 between which the arc is formed, and Fig. 2 is a cross-section of the electrode which contains the light-giving material.

In the drawings, in which for the purposes of illustration I have shown the elec- 110

trodes axially alined, 1 is the electrode containing the light-giving material and 2 the electrode containing the steadyng material. The electrode 1 may conveniently be made of a body portion 3 of titanium carbid, as pure as it is practicable to produce, inclosed within a thin iron shell 4. The coöperating electrode 2 may be made of carbon impregnated with a solution of steadyng material, such as potassium baborate, and then dried. When the steadyng material is a salt of an alkali metal, I preferably impregnate the carbon electrode with a solution such that the finished electrode will contain approximately one per cent. of the steadyng salt. It is to be understood, however, that I am not confined to such percentage, as I may use more or less of the steadyng salt and still produce a useful electrode, nor is this specific method of impregnating the electrode a part of my invention.

In compliance with the patent statutes, I have shown one embodiment of my invention; but it is to be understood that my invention is susceptible of numerous modifications which come within the spirit thereof. For example, while I have referred to metallic titanium and titanium compounds as materials particularly suitable as light-giving materials for the purpose of my invention, it is to be understood that it is not limited to such materials, but covers any light-producing material of a more or less refractory nature. Furthermore, while I have named potassium baborate as a specific example of a steadyng compound, it is to be understood that any desirable steadyng material may be used, and I have especially found that potassium carbonate, potassium fluorid, sodium fluorid, potassium chlorid and calcium fluorid are all valuable steadyng agents, the selection of the steadyng compound depending upon the character of light which is desired and upon the character of the light-giving material in the other electrode with which the electrode containing the steadyng material coöperates. If calcium fluorid, for example, is used it will be found that it should be used in a larger percentage than the potassium baborate, preferably from 10 to 20 per cent. It is to be un-

derstood, of course, that more than one light-producing material, if desired, may be introduced from one electrode and that more than one steadyng material may be introduced to the arc from the other electrode.

I have also described my invention as particularly applicable to systems on which alternating currents are used, but it is to be understood that my invention is not limited to such systems but may be used in arc lamps in which direct currents are employed, in which case the light-producing material is carried into the arc by electro-conduction while the steadyng material is carried thereto merely by evaporation or vice versa. It is further to be understood that while for the purposes of illustration I have shown my invention embodied in vertically alined electrodes, it can be used equally well with converging ones, or with any other desired arrangement of electrodes.

Any suitable mechanism may be employed for striking and regulating the arc. Such structures are well known in the art and I have not deemed it necessary to describe any specific mechanism.

What I claim as new, and desire to secure by Letters Patent of the United States, is,—

1. The method of producing a flaming or luminous arc which consists in introducing a light-giving material into the arc from one electrode only and a steadyng material from the companion electrode only.

2. The combination of a pair of electrodes for producing a luminous or flaming arc, one of which is the sole source of light giving vapors for the arc and the other is the sole source of steadyng vapors for the same.

3. The combination of a pair of electrodes for producing a luminous or flaming arc, one of which contains material which is the sole source of the light giving vapors in the arc, and the other contains material which is the sole source of steadyng vapors in the arc.

In witness whereof, I have hereunto set my hand this 24th day of April, 1911.

JOSEPH L. R. HAYDEN.
